POLE ATTACHMENT

Lester D. Warwick, Denver, Colo.

Application June 21, 1946, Serial No. 678,503

8 Claims. (Cl. 294—19)

1

This invention relates to improvements in high voltage line maintenance equipment and has reference more particularly to an improved pole attachment for use in repairing and replacing broken insulators and cross arms, as well as for many other purposes.

High voltage transmission lines of the type now extensively employed, require repairs to be made from time to time and since it is quite essential that the power shall not be disconnected during the time that the repairs are made, it is necessary for the linemen to be provided with the proper equipment and the necessary training for manipulating the live wires and putting them in such position that repairs can safely be made.

The need for special tools for this purpose has been recognized and various tools are available on the market, that can be employed for the purpose above indicated. Such tools, however, although they can be employed by properly trained linemen in such a way as to make it possible to effect required maintenance repairs safely, are expensive and can be used only by persons who have been carefully trained to do so.

It is the object of this invention to produce a pole attachment that can be readily secured to a transmission pole or to a cross arm for the purpose of supporting gin poles and/or pigtail sticks and other apparatus that may be necessary for the particular operation.

Another object is to produce a pole attachment that can be quickly and accurately secured to a cross arm for the purpose of insulator replacement or, by means of lag screws, to the pole itself, where cross arms are to be replaced.

The above and other objects that may become apparent as this description proceeds are attained by means of a construction and an arrangement of parts that will now be described in detail and for this purpose reference will be had to the accompanying drawing in which the invention has been illustrated in its preferred form, and in which:

Figure 1 is an edge elevational view of the pole attachment that forms the subject of this invention;

Figure 2 is a front side elevation looking in the direction of arrow 2 in Figure 1;

Figure 3 is a top plan view;

Figure 4 is a fragmentary side view to a somewhat enlarged scale, looking in the direction of arrows 4—4, in Figures 3 and 5;

Figure 5 is a section taken on line 5—5, Figure 4;

2

Figure 6 is a side elevation of a pole employed for attaching the device to a cross arm;

Figure 7 is a side elevation of a specially constructed pole for use in securing and spreading transmission wires;

Figure 8 is a view showing the attachment secured to one end of a cross arm and illustrates how the wire is supported during the replacement of an insulator;

10 Figure 9 is a section taken on line 9—9, Figure 8, showing a portion of the attachment in place on a cross arm;

Figure 10 is a view showing the attachment in position on the upper end of a pole and secured thereto for holding the wires in position while the cross arm is replaced or repaired; and

15 Figure 11 is a fragmentary edge elevation of the attachment showing the manner in which it is secured to a pole.

20 In the drawing reference numeral 15 designates a transmission line pole and reference numeral 16 a cross arm. The cross arm is provided with insulators 17 of any approved construction. Where a three-faced transmission circuit is used,

25 three insulators are arranged on the cross arm in the manner shown in Figure 10 which illustrates the most usual and simplest construction. Some transmission lines employ what is known as a ridge pin construction for one wire, which

30 comprises an insulator positioned on the top of the pole. However, for the purpose of the present description the construction shown in Figure 10 is believed to be sufficient. The pole attachment which forms the subject of this invention has been indicated in its entirety in Figures 8, 9, 10 and 11 by reference numeral 18 and its construction has been shown in detail in Figures 1 to 5, inclusive, to which reference will now be made.

35 40 The attachment consists of a bar 19 that is split downwardly from the upper end forming two fingers 20 that are spread outwardly as shown in Figure 2. The fingers are bent rearwardly at right angles forming hooks 21 that terminate in downwardly extending portions 22. The hooks are provided with holes 23 for a purpose which will hereinafter appear. Secured to the outer surface of bar 19 is a cross bar 24 that may be welded or secured in position by means of rivets

45 50 55 25. Extending rearwardly from the inner surface of cross bar 24 is a lug 26 that has a threaded opening 27. Extending inwardly from bar 19 are four pins 28 terminating in sharpened conical ends 29. Positioned adjacent pins 28 are holes for the reception of lag screws 30 whose

3

square heads have been shown in Figure 2. At its lower end bar 19 is provided with a number of holes 31 to which reference will hereinafter be made. Secured to the outer surface of bar 19 is a circular insulator 32 which is made from some highly efficient insulating material. The insulator must have, in addition to its high insulating properties, considerable strength and very low hygroscopic properties and any material that has these properties may be used. Insulator 32 has a cylindrical section of decreased diameter which has been designated by reference numeral 33. A cap 34 of insulating material, having a cylindrical wall 35, is positioned against the outer end of insulator 32 and mounted for rotation about part 33. Insulator 32 is secured to bar 19 by means of screws 35' or bolts, and the openings 36 are plugged with insulating material 37. The insulating cap 34 is secured in place by means of a bolt 38 that serves as a pivot and permits the parts to rotate relative to each other, but holds them in operative relation. Cap 34 is provided with openings 39 for the reception of latching pins that are used to hold the cap in rotary adjusted position. Insulator 32 is also provided with holes positioned at the same radial distance as holes 39 into which the latching pins project. One of these holes has been shown in Figure 4 and designated by numeral 40.

Four stud bolts 41 are threadedly connected with cover 34 at points equidistant from its center and arranged to form a square. Each bolt has a collar 42 that forms the outer abutment for a sleeve 43 which is mounted for free rotation thereon. The outer ends are threaded as shown at 44. A plate 45 has four openings positioned to receive the bolts and is held in place by nuts 46. Plate 45 has oppositely positioned cutouts 47 which give access to holes 39 to permit pins to be inserted to secure parts 32 and 34 against relative rotation.

Let us now assume that an insulator on arm 16 is to be replaced. The lineman positions the pole attachment as shown in Figure 8 or to one side of the insulator. The tie wire is removed after which a pigtail stick 48 is attached to the wire W. Plate 45 is now removed and stick 48 positioned between rollers 43 after which plate 45 is reapplied. A live line block 49 and treated rope 50 are now attached as shown in Figure 8. Of course a double block may be employed if desired; the single block has been shown for the purpose of illustration only. The rope is now subjected to a pull P sufficient to raise the high tension wire after which the rope is anchored. With wire W in the position shown in Figure 8, the insulator may be replaced with safety, after which the wire is lowered onto the insulator and secured to it by a suitable tie wire. The pigtail stick is now removed. Reference is now made to Figure 9 which shows that after the attachment has been hooked over cross arm 16, the threaded end 51 at the end of the insulating stick 52 is inserted in the threaded opening 27 in lug 26 and turned until the end of 51 engages the lower surface of the cross arm, whereupon the attachment will be securely attached to the cross arm. In order to support the stick at any given angle, a pin must be inserted in holes 39 and 40.

Let us now assume a case in which the cross arm is to be replaced. The attachment is secured to the post above the cross arm as shown in Figure 10 by means shown in Figure 11. Two or more lag screws 30 are screwed into the post 78

with sufficient force to sink points 29 of pins 28 into the wood. Pigtail stick is now attached to the middle wire, after which it is secured in place between rollers 43 by plate 45. By means of the rope and block the wire is raised and held in elevated position by the gin pole 48.

Poles 51, of approved insulating material, are now employed to support and spread the other two wires in a manner which will now be described. Pole 51 is provided at one end with a ferrule 52 to which is threadedly attached a hook 53. The other end has a ferrule 54 to which is threadedly attached a bolt 55 having a head 56 from one side of which a bolt 57 projects and this has a nut 58. Each side wire is engaged by a hook 53 and the stick turned until the ferrule closes the opening into the hook, whereupon the wire will be firmly secured to the stick; head 56 and bolt 55 are now rotated to get the proper length to permit bolt 57 to enter one of the holes 31. The nut is now applied to bolt 57. After both of the outside wires have been secured to the ends of sticks 51 and the latter pivotally connected with 19, the live line blocks 59 are attached as shown in Figure 10, hooks 60 engaging in holes 23. Tension is now applied to ropes 50A and the outside wires raised after which the ropes are securely anchored. The cross arm can now be removed and replaced after which the wires are lowered by a reverse action.

By the simple mechanism shown comprising the pole attachment, one gin pole 48 and two spreader sticks 51, the wires are removed from the cross arm and held safely suspended, which, heretofore has required the use of a large number of sticks, ropes, blocks, strain breaks and other pieces of apparatus. The great simplicity is due to the use of the pole attachment shown in Figures 1 to 5 and to the specially constructed spreader stick shown in Figure 7, which will form the subject of another application.

Attention is called to Figure 10 and to the fact that when the attachment is lagged to the post, the hooks serve as anchors for the blocks.

Having described the invention what is claimed as new is:

1. A device of the class described, for use in high tension line maintenance, comprising, a substantially flat steel bar of Y-shape, the upper ends of the forked members being formed into hooks for engaging over a cross arm, clamping means for securing it to the cross arm, an insulator attached to the outer surface of the bar, a pivot extending outwardly from the insulator, an insulator attached to the pivot for rotation thereon, means for interlocking the two insulators in any one of several rotary positions, and means for securing a gin pole to the outer insulator for longitudinal movement.

2. A device in accordance with claim 1 in which a plurality of sharpened pins project from the rear surface of the bar and in which the bar is provided with at least two openings for lag screws.

3. A device in accordance with claim 1 in which the hooks have openings for attaching a block thereto, and in which the lower end of the bar is provided with a plurality of openings.

4. A device of the class described, for use in high tension line live wire maintenance, comprising, a flat metal bar having two spaced, aligned hooks at its upper end for engaging over a cross arm, means comprising a clamping device for engaging the under surface of a cross

arm to secure the device in position thereon, an insulator secured to the outer surface of the bar, an insulator pivotally attached to the first insulator, means for latching the two insulators in any one of several relative rotary positions, a gin pole slidably connected with the second named insulator, and means comprising a rope and block, interconnecting the lower end of the gin pole and the lower end of the bar for moving the gin pole against an opposing force.

5. A device of the class described, for use in high tension line live wire maintenance, comprising, a flat metal bar having two spaced, aligned hooks at its upper end for engaging over a cross arm, a lug projecting rearwardly from the bar at a point below the hooks, the lug having a transverse threaded opening for the reception of a clamping bolt, a cylindrical insulator secured to the outer surface of the bar, an insulator attached to the first mentioned one for movement about a pivot, means for holding the two insulators in assembled relation comprising a pivot, means for interlocking the two insulators in any of several relative rotary positions, the outer surface of the outer insulator having a guideway for the reception of a gin pole, a gin pole in said guideway and means comprising a rope and block for moving the gin pole in the direction of its length against an opposing force.

6. A device of the class described, for use in high tension line live wire maintenance and repair, comprising a metal bar having its upper end formed into two spaced hooks adapted to

extend over a cross arm, two relatively rotatable insulators, one of which is attached to the side of the bar opposite from the hooks, means for interlocking the insulators in any of several angularly related positions, the outer insulator having its outer surface provided with a guide way, a gin pole, or the like, in the guide way, and means for moving the gin pole longitudinally against an opposing force.

10. 7. A device in accordance with claim 6 in which the bar is provided, on its rear surface, with at least two pair of sharpened pins, and with at least one hole for a lag screw adjacent each pair of pins, the hooks having openings for anchoring blocks thereto.
15. 8. An article of the class described, comprising a flat metal bar of Y-shape, the stem having a plurality of holes at its lower end, a plurality of pairs of sharpened pins projecting from its rear surface, there being at least one hole for the reception of a lag screw adjacent each pair of pins, the ends of the branches extending rearwardly at an angle of about 90 degrees, the ends having holes for anchoring blocks thereto, and a two-part insulator on the front of the bar, one of the insulators being secured in fixed position and the other pivotally connected therewith the pivotally mounted insulator having a diametrically extending guideway for the reception of a gin pole and means for interlocking the insulators in a plurality of angularly spaced positions.

LESTER D. WARWICK.
